UNITED STATES PATENT OFFICE

168,616

COMBINATION STOVE, SINK, AND
REFRIGERATOR UNIT

Alfonso Iannelli, Park Ridge, Ill.

Application May 6, 1952, Serial No. 19,612

Term of patent 14 years

(Cl. D33—19)

To all whom it may concern:

Be it known that I, Alfonso Iannelli, a citizen of the United States, residing at Park Ridge, in the county of Cook and State of Illinois, have invented a new, original, and ornamental Design for a Combination Stove, Sink, and Refrigerator Unit, of which the following is a specification, reference being had to the accompanying drawings, forming part thereof, wherein:

Fig. 1 is a perspective view showing the front and one side of a combination stove, sink, and refrigerator unit embodying my new design, the top of the unit and the doors on the front of the unit being shown in closed position;

Fig. 2 is a similar view showing the top in its open position; and

Fig. 3 is a perspective view showing the front and the opposite end of the unit with the top and doors illustrated in their open positions.

The back of the unit is plain and unornamented.

I claim:

The ornamental design for a combination stove, sink, and refrigerator unit, substantially as shown and described.

ALFONSO IANNELLI.
